CLAIM

The ornamental design for a combined vehicle side view mirror and antenna for am/fm/cb radio and cellular phone, as shown and described.

DESCRIPTION

FIG. 1 is a front, top and right side perspective view of a combined vehicle side view mirror and antenna for am/fm/cb radio and cellular phone, showing my new design;

FIG. 2 is a reduced scale rear, bottom and right side perspective view thereof; and,

FIG. 3 is a reduced scale front elevational view.
The left side, not shown, is the same as the right side.

FIG. 1

FIG. 2

FIG. 3
